UNITED STATES PATENT OFFICE

2,579,953

ADJUSTABLE SHOE GRIPPER

Naomi M. Morris, Cleveland, Ohio

Application February 13, 1951, Serial No. 210,687

1-Claim. (Cl. 36—7.6)

1

This invention relates to an adjustable shoe gripper, or more particularly, to an anti-slip attachment for shoes.

By way of background, it may be noted that walking upon a snowy or icy surface is always dangerous, and serious injury to persons slipping and falling on such a surface is quite common. This is true even where rubber overshoes having a cleated or roughened underside are used since the sole of the overshoe is not of a configuration or material that will enable it to grip the icy surface and prevent slipping.

Accordingly, the broad object of the present invention is to provide an attachment to a shoe, that will dig into and effectively grip the icy surface in such a manner as to eliminate any possibility of the wearer's slipping and falling upon the ice.

Another important object is to provide an attachment of the type stated which can be secured to the underside of a shoe with speed and ease.

Still another object is to provide an attachment as described which will be adjustable to fit shoes of any width or length.

Yet another object is to provide an attachment as described novelly formed to result in a particularly effective gripping action, through the provision of gripping bars extending along opposite sides of the device in converging relation, and equipped with pointed burrs, nails, or cleats, these cooperating with a circular centrally disposed heel plate underlying the heel of the shoe and equipped similarly with nails or cleats.

Still another object is to provide an attachment of the character described which will be ruggedly formed of metal material, which will have few parts simply arranged, and which will be nevertheless capable of being manufactured in a manner whereby it will be light and, to all intents and purposes, invisible when worn.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings,

Fig. 1 is a top plan view of the attachment.

Fig. 2 is a fragmentary bottom plan view.

Fig. 3 is an enlarged fragmentary perspective view of one of the gripping bars.

Fig. 4 is a fragmentary perspective view of one of the adjustable connections.

Referring to the drawings in detail, the device includes an elongated center bar 1, adapted to extend longitudinally and centrally of the sole of a wearer's shoe, not shown. The center bar 1

2

is formed from a length of flat bar stock, and is preferably of steel or iron, so as to be rugged, and long wearing.

The center bar 1 would extend to a location 5 immediately rearward of the tip of the wearer's shoe, at the front end of said center bar. Formed in the top surface of the center bar, at its rear end, is a longitudinal recess 2, opening upon the rear end of the center bar, the recess 2 having formed in its bottom surface a longitudinal series 10 of threaded openings 3.

Intermediate its opposite ends, the center bar 1 is integrally formed with a cross piece 4, disposed at right angles to the center bar, the cross piece 4 having one end portion extended laterally a substantial distance, so as to terminate barely short of one side of the sole of the wearer's shoe. Said laterally extended end portion of the cross piece 4 is integrally formed with an arcuate gripping member 5, the integral connection of the gripping member 5 to the cross piece 4 being disposed intermediate opposite ends of the gripping member 5, but closer to the rear end thereof.

The other end of the cross piece 4 is extended 25 only a short distance beyond the center bar 1, and is formed with a longitudinal recess 6 like the recess 2, the recess 6 having a longitudinal series 20 of threaded openings 7.

Received in the recess 6 is one end of a connecting bar 8, having at opposite ends pairs of openings receiving screws 9 and 10 respectively. The screws 9 are threadable into any adjacent pair of openings 7, while the screws 10 are threaded into threaded openings formed in an 35 inwardly extended lateral projection 12 formed upon the intermediate portion of a gripping member 13.

As will be seen, the gripping member 13 is 40 capable of being adjusted laterally toward or away from its cooperating gripping member 5, so as to adjust the device to the width of the particular shoe.

It may be noted that the front portions of the members 1, 5, and 13 all extend forwardly in converging relationship, in general correspondence 45 to the generally tapered tip construction of a shoe. In this way, the sole of the shoe will be effectively equipped with gripping means, that will extend from the front of said sole to a location close to the heel of the shoe, along opposite side edges of the sole.

To hold the front end portion of the device in proper position upon the underside of a shoe, I provide rings 14 welded or otherwise rigidly secured to the respective gripping members 5 and 13, intermediate opposite ends of the gripping members, the rings respectively accommodating strap sections 15 and 16 capable of being adjustably connected after being extended over the 55 upper of the shoe.

Received in the recess 2 of the center bar 1 is a connecting bar 17, having screws at opposite ends threaded into any selected openings 3, for the purpose of adjusting the device as to length, the screws at the other end of the connecting bar being received in threaded openings formed in a forwardly extended projection 18 integral with a circular heel piece 19 adapted to underlie the heel of the wearer's shoe.

At its rear end the heel piece is provided with an upwardly extended ring 20 welded or otherwise rigidly secured to the heel piece, this having secured thereto oppositely extending strap sections 21 that are capable of being adjustably secured after being extended around the top part of the wearer's shoe, or around the wearer's ankle, as the case may be.

On the underside of the heel piece 19, as well as on the undersides of the gripping members 5 and 13, there are provided a plurality of downwardly extending pointed cleats, burrs, or nails, integrally secured in place and adapted to dig into the snowy or icy surface for the purpose of preventing slipping. These extend over the full area of the heel piece, as readily seen from Fig. 2, and are extended longitudinally of the gripping members for the full lengths thereof.

I believe it will be sufficiently apparent as not to require special illustration that the cross bar 4 and the center bar 1 can as well be provided throughout their lengths with cleats 23, if so desired.

Of importance is the fact that the gripping members, center bar, cross bar, heel piece, and connecting bars are all disposed with their top surfaces co-planar, so as to provide a plane surface upon the entire attachment, whereby it will be capable of being fitted snugly to the underside of the wearer's shoe and will be invisible to all intents and purposes when being worn, with the exception of course of the straps.

What is claimed is:

An anti-slip attachment for shoes comprising an elongated flat center bar adapted to extend substantially longitudinally and centrally of and

underlie the sole of a shoe, said center bar having a longitudinal recess in its rear end, a cross piece rigid with the medial portion of the center bar and having a longitudinal recess in one end thereof, a gripping member proportioned to underlie one side of a shoe sole, a connecting bar secured at one end to said gripping member, the connecting bar extending into the recess of the cross piece at its other end, means for attaching said last-named end of the connecting bar in selected positions of adjustment longitudinally of the cross bar, for adjustment of the gripping member toward and away from the center bar, a second gripping member rigid with the opposite end of the cross bar and adapted to underlie the opposite side portion of a shoe, a heel piece spaced rearwardly from the center bar, a connecting bar secured at opposite ends to the heel piece and in the center bar recess respectively, the connection of the connecting bar last-named to the center bar being adjustable longitudinally of the center bar, and means on the undersides of the heel piece and the respective gripping members adapted to grip an icy surface or the like, said means comprising a plurality of spaced depending pointed cleats, said gripping members and heel piece having means for attachment to a shoe.
